Fig. 4

To all whom it may concern:

Be it known that I, Howard L. Paulus, have invented a new, original, and ornamental Design for an Automobile Air Conditioner, of which the following is a specification, reference being had to the accompanying drawing, forming a part hereof.

Fig. 1 is a perspective view of an automobile air conditioner embodying my new design.

Fig. 2 is a plan view of the automobile air conditioner shown in Fig. 1.

Fig. 3 is a front view of the automobile air conditioner shown in Fig. 1.

Fig. 4 is a rear view of the automobile air conditioner shown in Fig. 1.

Fig. 5 is a right hand side view of the automobile air conditioner shown in Fig. 1.

I claim:

The ornamental design for an automobile air conditioner, as shown.
